FIRE ENGINE PUMP ASSEMBLY

Benjamin D. Barton and Adrian P. Adney, Battle Creek, Mich., assignors to American-Marsh Pumps, Inc., Battle Creek, Mich.

Application November 18, 1943, Serial No. 510,766

5 Claims. (Cl. 169—24)

This invention relates to improvements in fire engine pump assembly.

The main objects of this invention are:

First, to provide a fire engine pump assembly which is adapted for embodiment in commercial types of trucks without substantial adaptation or reconstruction thereof.

Second, to provide a structure having these advantages in which the valve connection between the pump and the delivery conduit is readily accessible for cleaning and may be easily removed and replaced without disturbing heavy parts.

Objects pertaining to details and economies of the invention will definitely appear from the description to follow. The invention is defined in the claims.

A structure which embodies the features of the invention is clearly illustrated in the accompanying drawing, in which:

Fig. 1 is a fragmentary plan view of an embodiment of the invention, only such portions of a truck or vehicle being illustrated as seen to be necessary to afford an understanding of the invention and the manner of adapting the same.

Fig. 2 is an enlarged fragmentary view on line 2—2 of Figs. 1 and 3.

Fig. 3 is a horizontal section on line 3—3 of Fig. 2.

Fig. 4 is a sectional view on a line corresponding to line 4—4 of Figs. 1 and 2.

Fig. 5 is a side elevation of the check valve and its casing.

In the accompanying drawing 1, 1 represents the longitudinal sills of a motor vehicle chassis and 2, 2 the side walls of the vehicle body. The pump intake conduit 3 is mounted transversely of the chassis with its ends projecting through openings 4 provided therefor in the side walls 2. This intake conduit is provided with a connection 5 at either end for a hose 6 leading to a source of supply, a closure 7 being provided for the other end of the conduit. The delivery conduit 8 is disposed transversely of the chassis in laterally spaced relation to the inlet conduit. This delivery conduit is provided with a valve 9 at either end, only one being illustrated, and means 10 for connecting a hose thereto. These conduits are preferably formed with mounting brackets 11 although it will be understood that they may be otherwise mounted. They are fixedly supported, however. The delivery conduit is provided with a side inlet 12.

The pump, designated generally by the numeral

13, is designed to be driven from the motor vehicle, the driving connections not being illustrated. This pump is mounted on the conduits 3 and 8, but the details of mounting are not illustrated. The pump is provided with a discharge 14, the flanged end 15 of which is disposed adjacent to but in spaced relation to the inlet 12, see Figs. 2 and 3.

The casing 16 for the check valve 17 is interposed between the end of the pump discharge 14 and the inlet 12 of the delivery conduit. This valve casing is preferably of uniform thickness, its sides being parallel so that it may be introduced between and removed from between the pump discharge and the delivery conduit inlet by a lateral sliding movement. It is secured in its adjusted position by means of the lag screws 18 which are arranged through the flange 15 on the end of the pump discharge 14 and are tapped into the walls of the delivery conduit. Gaskets 19 are arranged between the valve casing and the pump discharge and between the valve casing and the edges of the conduit inlet 12.

25 In use the check valves in this relation become fouled so that they do not function effectively for the reason that the source of water supply is frequently a ditch or stream, or other source in which more or less foreign substance is carried by the water. This feature of the ready removal of the valve permits the quick cleaning of the valve.

This apparatus may also be used generally as a pumping apparatus for pumping water from ditches, flooded excavations or the like. With the parts arranged as provided for by this invention the valve may be easily removed for cleaning without disturbing the heavier parts and without the necessity of disconnecting the pump from its driving connections. A further advantage is that inasmuch as the intake and delivery conduits are arranged through the walls of the body it has heretofore been a difficult and time consuming matter to remove the valve for cleaning and replacement.

40 We have illustrated and described the invention in a practical embodiment thereof. No attempt has been made to illustrate other adaptations which are possible as it is believed this disclosure will enable the adaptation of the invention as may be desired.

Having thus described our invention what is claimed as new and desired to secure by Letters Patent is:

55 1. In a fire apparatus, the combination with

a chassis and a body comprising side walls on the opposite sides of said chassis, of a pump intake conduit mounted on said chassis transversely thereof, said intake conduit having opposite ends thereof projecting through said body side walls, said intake conduit being adapted for connection at either projecting end thereof with a source of supply, a delivery conduit disposed transversely of the chassis and in parallel and laterally spaced relation to said intake conduit, said delivery conduit having opposite ends thereof projecting through said side walls, said delivery conduit having a side inlet and being provided at either projecting end with connecting means, a pump fixedly connected to said conduits and disposed between the said side walls and also disposed in a plane between said conduits and having a discharge connection adjacent to but spaced from said delivery conduit inlet, a return check valve comprising a casing interposed between the end of the pump discharge and the inlet of said delivery conduit, said delivery conduit and pump being fixedly held relative to each other independently of said valve casing, said valve casing being adapted to be inserted and removed from between said pump discharge and said delivery conduit inlet by a lateral movement of the valve casing and without relative shifting of the pump or of the delivery conduit from their fixedly held positions relatively to each other, and means for removably securing the valve casing in position, said valve casing constituting a coupling for said pump discharge to said delivery conduit.

2. In a fire apparatus for vehicles having a chassis and a body portion with side walls on the opposite sides of said chassis, the combination of a pump intake conduit adapted to be mounted on said chassis with an end projecting through one of said body side walls, a delivery conduit disposed in parallel spaced relation to said intake conduit and having an end adapted to project through one of said side walls, said delivery conduit having a side inlet, a pump fixedly connected to said conduits and having a discharge connection adjacent to but spaced from said delivery conduit inlet, a return check valve comprising a casing interposed between the end of the pump discharge and the inlet of said delivery conduit, said delivery conduit and pump being fixedly held relative to each other independently of said valve casing, said valve casing being adapted to be inserted and removed from between said pump discharge and said delivery conduit inlet by a lateral movement of the valve casing and without relative shifting of the pump or of the delivery conduit from their fixedly held positions relative to each other, and means for removably securing the valve casing in position, said valve casing constituting a coupling for said pump discharge to said delivery conduit.

3. In a fire apparatus for vehicles having a chassis and a body portion with side walls on the opposite sides of said chassis, the combination of a pump intake conduit adapted to be mounted on said chassis with an end projecting through one of said body side walls, a delivery conduit disposed in parallel spaced relation to

said intake conduit and having an end adapted to project through one of said side walls, said delivery conduit having a side inlet, a pump fixedly connected to said conduits and having a discharge connection adjacent to but spaced from said delivery conduit inlet, a return check valve comprising a casing interposed between the end of the pump discharge and the inlet of said delivery conduit, said delivery conduit and pump being fixedly held relative to each other independently of said valve casing, said valve casing being of uniform thickness and adapted to be inserted and removed from between said pump discharge and said delivery conduit inlet by a lateral movement of the valve casing and without relative shifting of the pump or of the delivery conduit from their fixedly held positions relative to each other, and means for removably securing the valve casing in position, said valve casing constituting a coupling for said pump discharge to said delivery conduit.

4. In a pumping apparatus, the combination with a support, of a pump intake conduit mounted on said support, a delivery conduit mounted on said support in laterally spaced relation to said intake conduit, said delivery conduit having a side inlet, a fixedly mounted pump having a discharge connection adjacent to but spaced from said delivery conduit inlet, a valve comprising a casing interposed between the end of the pump discharge and the inlet of said delivery conduit, said delivery conduit and pump being fixedly held relative to each other independently of said valve casing, said valve casing being of uniform thickness and adapted to be inserted and removed from between said pump discharge and said delivery conduit inlet by a lateral movement of the valve casing and without relative shifting of the pump or of the delivery conduit from their fixedly held positions relative to each other, and means for removably securing the valve casing in position, said valve casing constituting a coupling for said pump discharge to said delivery conduit.

5. In a pumping apparatus, the combination with a support, of a pump intake conduit mounted on said support, a delivery conduit mounted on said support in laterally spaced relation to said intake conduit, said delivery conduit having a side inlet, a fixedly mounted pump having a discharge connection adjacent to but spaced from said delivery conduit inlet, a valve comprising a casing interposed between the end of the pump discharge and the inlet of said delivery conduit, said delivery conduit and pump being fixedly held relative to each other independently of said valve casing, said valve casing being adapted to be inserted and removed from between said pump discharge and said delivery conduit inlet by a lateral movement of the valve casing and without relative shifting of the pump or of the delivery conduit from their fixedly held positions relative to each other, and means for removably securing the valve casing in position, said valve casing constituting a coupling for said pump discharge to said delivery conduit.
